Primary Examiner — Richard Kearney*Assistant Examiner* — Amber R Lee(74) *Attorney, Agent, or Firm* — Knobbe, Martens, Olson & Bear, LLP**CLAIM**

The ornamental design for an amplifier mounted guitar stand assembly, as shown and described.

DESCRIPTION

FIG. 1 is a top perspective view of an amplifier mounted guitar stand assembly;

FIG. 2 is a right side view of the amplifier mounted guitar stand assembly of FIG. 1;

FIG. 3 is a left side view of the amplifier mounted guitar stand assembly of FIG. 1;

FIG. 4 is a front side view of the amplifier mounted guitar stand assembly of FIG. 1;

FIG. 5 is a back side view of the amplifier mounted guitar stand assembly of FIG. 1;

FIG. 6 is a top side view of the amplifier mounted guitar stand assembly of FIG. 1; and,

FIG. 7 is a bottom side view of the amplifier mounted guitar stand assembly of FIG. 1.

All features in broken lines are for the purpose of illustrating environmental structure and form no part of the claimed subject matter.
